UNITED STATES PATENT OFFICE.

ELMER C. LOCHHEAD AND LESTER PAUL BREWER, OF EFFINGHAM, ILLINOIS.

ATTACHMENT FOR MACHINES FOR SEWING LOOPED FABRICS.

1,389,520.

Specification of Letters Patent. Patented Aug. 30, 1921.

Application filed March 23, 1920. Serial No. 368,040.

To all whom it may concern:

Be it known that we, ELMER C. LOCHHEAD and LESTER P. BREWER, citizens of the United States, residing at Effingham, in the county of Effingham and State of Illinois, have invented a new and useful Improvement in Attachments for Machines for Sewing Looped Fabrics, of which the following is a specification.

10 This invention relates to improvements in machines for sewing looped fabrics in which the thread is automatically cut and the fabric removed from the machine.

15 The object of the invention is to provide an attachment for automatically cutting the thread by which the knitted or woven fabric is looped or sewed together, and to automatically remove the finished article from the machine when the thread is cut.

20 Another object of the invention is to provide simple and efficient means for engaging the seam of the article carried by the looper dial and force said seam away from the dial and the stocking toward the dial 25 and guiding means for engaging said seam so that when the chain or thread connecting the article is reached it will be guided onto the cutter and severed thereby.

With these and other objects in view, 30 the invention consists in certain novel features of construction as hereinafter shown and described, and specifically pointed out in the claims.

In the accompanying drawing:

35 Fig. 1 represents a perspective view of a portion of a machine with this improved attachment shown applied.

Fig. 2 represents a perspective view of the attachment detached.

40 Fig. 3 is a side elevation of the knife carrying arm thereof; and

Fig. 4 is a top plan view of said arm.

Similar numerals refer to similar parts throughout the several views.

45 The attachment constituting this invention is shown applied to a conventional form of machine for uniting or sewing together the edges of knit goods or loose fabrics and in which A represents the fixed dial and B

50 the rotating dial which carries at its periphery the impaling pins or looper points C and from which the stockings or other articles D to be looped or sewed are suspended, one stitch only remaining on each point.

55 This stitch or loop is caught by the curved

looper needle, not shown, and sewed shut or closed with a loop or lock stitch. After being sewed the stocking passes on around with the movement of the dial B to a point where it passes between the base of the 60 looper dial and an auxiliary angle guide, shown at 47 and hereinafter described.

The attachment constituting this invention comprises a casting adapted to be attached to the fixed dial A of the looping or 65 sewing machine by a bolt or other suitable means. To this casting 1 is attached an arm 4 by means of a bolt 5 passing through a slot 7 in said arm and entering the casting which provides for the lengthening 70 or shortening of the arm 4. The arm 4 terminates in a tapered nose 8 which lifts the thread or chain E which connects the articles D such as stockings or the like and conveys it to the cutting edge of a knife 75 9 which rests in a groove 10 in the upper edge of the nose 8 of arm 4, and is held in place by a clamp 11 provided with a groove 12 to fit over the arm 4 and which is secured by set screws as 13 on either side of 80 clamp 11.

The cutting edge of knife 9 is protected by a guard 15 which is in the form of a flat strip fastened at one end to the clamp 11 by a screw 16. The arm 4 is held stationary 85 by a lock 18 which is fastened to the casting 1 by a bolt 19.

A remover 22 is attached to a support 23 which extends at right angles to arm 4 and is held in place by a spiral spring 27 which 90 is attached at one end to the remover 22 and is fastened at its other end to the support 23 and said support 23 is secured to the casting 1 at the opposite end by any suitable means.

To further the efficiency of this cutting and removing device there is attached a seam guide comprising an edgewise disposed holding arm 31 attached at one end to the casting 1 by the bolt 19 which passes 100 through a slot 32 in said arm 31. This arm has a twist therein intermediate its ends, whereby its slotted end is disposed vertically edgewise while its other end is flatwise.

A reciprocating guide lever 33 is pivoted at one end to the terminal of the flat end of the holding arm 31 by a bolt 34. A guide finger 38 is attached to the other end of the reciprocating guide lever 33 between a boss 110

43 thereof and a clamp bar 41. A groove 42 in the boss 43 of the lever 33, receives the guide finger 38 and said lever 33 is further connected to the holding arm 31 by a spiral 5 spring 44 which is attached at one end to the lever 33 midway its ends and at its other end to the holding arm 31.

An auxiliary angle guide 47 is connected to the reciprocating guide lever 33 by a 10 threaded bolt 48 passing through a slot in the lever 33 and fastened by means of the nuts 50 and 51 and also by the bolt 48 passing through the auxiliary angle guide 47 and fastened by means of nuts 53 and 54.

15 In the use of this attachment the parts being in the position shown in Fig. 1, the thickness of the stocking D forces the angle guide 47 out from the looper dial and in so doing the guide finger 38 presses the seam 20 of the stocking away from the dial as shown at the right of Fig. 1. Owing to the fact that the toe of the stocking is tucked under the foot in the operation of looping, the stocking will be thicker between the two ends 25 of the toe or rather between the corners of the toe. The plow shaped nose 8 of the holding arm 4 rides along the seam at its inner side and pushes the seam out against the tension of the member 47 so that when the 30 thread or chain connecting two stockings is reached, the plow shaped nose 8 will project under said chain and cause it to ride up on the nose and be guided onto the knife 9. This thread is placed under tension incident 35 to the movement of the dial away from the knife 9 and this tension on the thread causes the knife 9 to sever the thread which connects the stocking, the severed ends of which are shown at the left of Fig. 1.

40 After the thread has been severed, the continued movement of the dial will bring the stocking into engagement with the member 22 which will operate to force the stocking off the looper points as shown at the 45 left of Fig. 1, and the finished article will drop down on the floor or into a receptacle placed to receive it.

What is claimed is:

1. In a machine for sewing looped fabrics, the combination with a ring support having an impaling pin carrying ring rotarily mounted thereon, of a thread cutting mechanism mounted on said support and comprising a seam engaging nose extending 55 beyond the perimeter of said ring, a cutter carried by said nose, and means for directing the seam toward said nose whereby the nose will extend under the thread to be cut and guide it against said cutter.

60 2. In a machine for sewing looped fabrics, the combination with a ring support, having an impaling pin carrying ring rotarily mounted thereon, of a thread cutting mechanism mounted on said support and comprising 65 a seam engaging nose extending beyond

the perimeter of said ring, and arranged tangentially relatively thereto with its point facing in the direction opposed to that in which said ring turns to insure the passage of the nose under the thread to be cut, and a cutter carried by said nose and on to which the thread is directed by the rotation of said ring.

3. In a machine for sewing looped fabrics, the combination with a ring support 75 having an impaling pin carrying ring rotarily mounted thereon, of a thread cutting mechanism mounted on said support and comprising a seam engaging tapered nose extending beyond the perimeter of said ring, 80 and a cutter mounted longitudinally on the upper face of said nose to engage the thread directed thereon by said nose and sever it.

4. In a machine for sewing looped fabrics, the combination with a ring support, 85 having an impaling pin carrying ring rotarily mounted thereon, of a thread cutting mechanism mounted on said support and comprising a seam engaging nose extending 90 beyond the perimeter of said ring, a cutter carried by said nose, and a guard for said cutter arranged thereover.

5. In a machine for sewing looped fabrics, the combination with a ring support, having an impaling pin carrying ring rotarily mounted thereon, of a casting mounted on said support, an arm carried by said casting and extending tangentially relatively to said ring and provided at its outer end with a tapered nose projecting beyond the 100 perimeter of the ring, a cutter carried by said nose, said nose facing in a direction opposite to that in which said ring turns to insure the passage of the nose under the thread to be cut, and means for directing the 105 seam toward said nose whereby the nose will extend under the thread to be cut and guide it against said cutter.

6. An attachment of the class described, comprising a casting to be mounted on a 110 ring support on a machine for sewing looped fabrics, an arm mounted for longitudinal adjustment on said casting and provided at its front end with a tapered nose, a knife carried by said nose, a guard arranged over 115 said knife, and means carried by said casting and positioned in advance of said nose for directing the seam toward said nose whereby the thread to be cut will be guided by said nose and directed against said knife. 120

7. An attachment of the class described, comprising a supporting and attaching member, an arm mounted for longitudinal adjustment on said member, a cutter detachably mounted on said arm, another arm 125 mounted on said member parallel with the first mentioned arm and in a plane above said first mentioned arm, a guide lever pivoted at one end to the free end of said second mentioned arm, a coil spring connecting said 130

lever intermediate its ends with said arm, a guide finger depending from the free end of said lever, and an angle guide depending from said lever intermediate its ends, said finger and angle guide being adapted one to engage the inner face of the seam of the article being sewed and the other the outer face thereof, said angle guide being designed to direct the thread to be cut onto said cutter.

8. An attachment of the class described, comprising a supporting and attaching member, an arm mounted for longitudinal adjustment on said member, a cutter detachably mounted on said arm, another arm mounted on said member parallel with the first mentioned arm and in a plane above said first mentioned arm, a guide lever pivoted at one end to the free end of the second mentioned arm, a coil spring connecting said lever intermediate its ends with said arm, a guide finger depending from the free end of said lever, and an angle guide depending from said lever intermediate its ends, said finger and angle guide being adapted one to engage the inner face of the seam of the article being sewed and the other the outer face thereof, said angle guide being designed to direct the thread to be cut onto said cutter, and an article removing member extending at right angles from said attaching member to position it in rear and spaced from said cutter to adapt it to operate on the article separated by the cutter.

9. An attachment of the class described, including an attaching member, an arm extending therefrom and having a tapered nose at its free end, said nose having its upper edge longitudinally grooved to form a knife receiving seat, and a clamp for detachably securing said knife in operative position.

10. An attachment of the class described including an attaching member, an arm extending therefrom and having a tapered nose at its free end, said nose having its upper edge longitudinally grooved to form a knife receiving seat, and a clamp for detachably securing said knife in operative position, and a guard carried by said clamp above said knife with its free end deflected

upward to facilitate the passage of the thread to be cut between it and the knife.

11. An attachment of the class described including a cutter, an arm arranged in a plane thereabove and projecting in advance thereof, a lever pivoted at one end to the free end of said arm, a depending guide finger carried by the free end of said lever, a coiled spring connecting said lever intermediate its ends with said arm whereby said finger is normally deflected, a screw threaded rod depending from said lever intermediate its ends having adjustably mounted thereon an angle guide mounted for co-operation with said finger to direct the thread to be cut toward the cutter.

12. In a machine for sewing looped fabrics, the combination with a ring support having an impaling pin carrying ring rotarily mounted thereon; of a thread cutting mechanism mounted on said support and comprising a seam engaging nose extending beyond the perimeter of said ring, a cutter carried by said nose, and means located in advance of said nose for directing the seam onto said nose whereby the thread to be cut will be guided by said nose against said cutter.

13. In a machine for sewing looped fabrics, the combination with a ring support having an impaling pin-carrying ring rotarily mounted thereon; of a thread cutting mechanism mounted on said support and comprising a seam engaging nose extending beyond the perimeter of said ring, a cutter carried by said nose, and means for directing the seam toward said nose whereby the nose will extend under the thread to be cut and guide it against said cutter, said means comprising elements arranged one to engage the outer face of the article being sewed below the seam thereof, and the other engaging the inner face of the seam, said elements being so connected that the article bearing against the element engaging its outer face will operate to cause the other element to force the seam away from the looper dial into position to be engaged by said nose.
